HENRY H. BABCOCK, OF WATERTOWN, NEW YORK.

Design No. 3,377, dated February 16, 1869.

DESIGN FOR A PUMP.

The Schedule referred to in these Letters Patent and making part of the same.

To all whom it may concern:

Be it known that I, HENRY H. BABCOCK, of Watertown, in the State of New York, have originated a new Design for Pumps, of which the following is a full, clear, and exact description, reference being had to the accompanying drawings, making part of this specification.

This design has reference to that part of a wooden pump which is above the well-curb, and contemplates a cylinder, *a*, having an octagonal pedestal, *b*, of about one-fifth the length of the pump.

A similar octagonal facing, *c*, forms the exterior of a portion of, perhaps, one-sixth the length of the pump, and a little above its centre.

Two mouldings, *a' a'*, are placed, one above and the

other below the facing *c*, and at equal distances therefrom.

The top of the pump is ornamented with a conic cap, *d*.

This I consider a neat and tasteful shape for pump, the octagonal facings and the mouldings in parting an elegant finish.

What I claim as my invention, and desire to secure by Letters Patent, is—

The design for pumps herein set forth.

HENRY H. BABCOCK.
